UNITED STATES PATENT OFFICE

CHARLES E. EGAN, OF CHICAGO, ILLINOIS, ASSIGNOR TO THE EGAN ELECTRIC AND TELEPHONE MANUFACTURING COMPANY, OF PETERSBURG, ILLINOIS, A CORPORATION OF ILLINOIS.

TELEPHONE SYSTEM AND APPARATUS.

No. 801,779.

Specification of Letters Patent.

Patented Oct. 10, 1905.

Application filed September 29, 1904. Serial No. 226,504.

To all whom it may concern:

Be it known that I, CHARLES E. EGAN, a citizen of the United States, residing at Chicago, State of Illinois, have invented certain new and useful Improvements in Telephone Systems and Apparatus, of which the following is a specification, reference being had therein to the accompanying drawings.

My invention relates to telephones and telephone systems, and particularly to such as are adapted for use with so-called "common battery" or "central energy" supply.

It is the object of my invention to produce an instrument and a circuit therefor which shall be simple and adaptable for use with any central-office circuit, while the instrument set itself shall be very compact and the number of its parts reduced to a minimum, all this without sacrifice of commercial efficiency.

More specifically stated, it is the object of my invention to construct a compact subscriber's instrument for central-energy lines in which the ringer and condenser are combined in a unitary piece of apparatus with all the other parts mounted or carried thereon. I am thus enabled to inclose my entire set in a very small box or casing, to reduce the cost of manufacture materially, and to render the handling and adjustment of the instrument much easier as well as more certain than in the prior type of instruments of this class.

A further object of the invention, also specifically stated, is to obviate the necessity for an impedance-coil separate from the other parts in the transmitter-circuit. This I accomplish by using a portion of the ringer-winding tapped off to the transmitter branch.

In assembling and mounting my instrument I provide a skeleton frame comprising a yoke and a side plate and mount the ringer-cores on the yoke and the armature-yoke on the cores. The switch-hook and its spring, together with the terminals of the receiver-cord with which its tips coöperate, are mounted upon the side plate, and the entire structure thus produced is mounted in the box or casing and supported from said yoke.

My invention is illustrated in the accompanying drawings, wherein—

Figure 1 is a front view of my box or casing with the parts mounted therein. Fig. 2 is a diagram of the same as it is actually wired. Fig. 3 is a diagram showing the parts con-

nected to a line-circuit during use of the apparatus. Fig. 3^a is a modified diagram of the subscriber's circuit as shown in Fig. 3.

Referring to the drawings, B is a box substantially square in shape and comprising a base b, having a bushed orifice b' for the admission of the circuit-wires, inclosing sides b², and a hinged lid B'. I mount my transmitter, preferably, upon the outside of this lid with a knuckle-joint and connect its circuit-wires t to the hinge-leaves b³, which are provided with the usual leaf-springs to insure a good connection. The inside wiring is taken to the transmitter through the twin leaves of the hinges, although it is to be understood that I do not limit myself to this, as I can substitute a flexible cord or other connection to the transmitter, if desired.

Upon the top of the box are the gongs G, between which plays the usual clapper, protected by a cap g. This clapper is carried upon the end of a rod g', rigidly attached to and vibrating with the armature q, which is pivoted at y² in a yoke y, supported upon the lower end of the cores j j' by means of the nuts y'. These cores lie parallel to each other and have their upper ends attached to and magnetically connected by the yoke J. This yoke also serves as a supporting means for the entire structure, being attached to the upper wall of the box by two screws or bolts f', preferably having terminal nuts on the outside of the box. The armature q is polarized, as are normally the cores, by a permanent magnet M, also carried on the yoke J.

Upon the core j' I place a winding Q of insulated wire, in most cases to a resistance of approximately one thousand ohms. This winding is shown, and the core is supposed to be approximately cylindrical in shape; but I wish to state that an important feature in the structure is the production of a high winding or a winding of large bulk in a space which shall not require the cores to be widely separated. I therefore make the winding in many cases and the core also oval or elliptical, with the short axis pointing toward the other core. The long axis would then be in the line of sight of Fig. 1. This elliptical form is indicated in Fig. 2. Upon the twin core j I place a wrapping of thin tin-foil sheets, separated by paraffined paper or similar material, to form a condenser. This is

rolled up to approximately the same size as the winding Q, and is marked C in all the figures. I contemplate making this also oval or elliptical in cross-section, whereby the flat 5 sides of the coil and condenser lie together, the long axes of the two ellipses being parallel. In this way a very considerable capacity can be obtained with small lateral dimensions.

10 Secured upon the yoke J is a side plate F, provided with two upwardly-extending arms f² f³, having their upper ends bent over upon the yoke and screwed or otherwise secured thereto. Upon the arm f² I mount 15 the two binding posts or terminals f⁶, which are bushed in the plate and insulated therefrom, as shown in Fig. 1. These binding-posts receive the tips r' of the flexible cord r, leading to the receiver R. This cord passes 20 out through a bushed opening r'' in one side of the box. The lower part of the plate F has a side extension f⁴, into which is threaded a shoulder-screw h', constituting the pivot for the hook-lever H, whose outer end extends 25 through the side of the box and is bifurcated at h to hold the receiver, whose weight normally holds it down against the force of the spring s, one end of which rests against a pin on the lever and the other end upon a pin set 30 into the plate F. Beneath the lever and mounted upon a forward extension or flange f⁵ of the plate F are the terminal contact-springs S, formed, preferably, of German silver with platinum contacts. One of these 35 springs is longer than the others and is engaged by a stud s', of insulating material, on the hook-lever, so that when the latter is down the lower springs are in contact; but when the lever is up the lower springs are 40 separated and the upper springs are forced together. Circuit connections of these springs are shown in Fig. 2.

Referring to Fig. 2, I show two line-terminals, No. 1 and No. 2. In case of a single-wire line one of these would be grounded. 45 In wiring the instrument the first terminal is connected to the winding Q and also by branch 8 to one of the upper contact-springs S. The other terminal is connected to one of 50 the receiver-terminals and also to the long spring of the hook-switch. The other connections of the coil and condenser, transmitter, receiver, and hook-switch are apparent without description. It will be observed 55 that the winding Q and the condenser C are permanently connected in series, and are thus bridged across the line in series with the receiver when the hook is up, a parallel bridge being then closed, however, through the 60 transmitter. When the hook is down, the receiver is shunted by a path of no resistance, and the transmitter branch is open. The principal feature of my circuit connections resides in the manner of utilizing the coil or 65 bobbin Q on the ringer for two separate

functions, usually performed by separate pieces of apparatus. When the hook is down—i. e., when the instrument is idle and connected to line for signaling-current only—the circuit is from No. 1 terminal through the wire 9 and the coil Q, through the condenser C and wires 12, 14, and 15, around the receiver, to terminal No. 2. Continuous current cannot pass through this path, by reason of the inclusion of the condenser C; but alternating or pulsating currents, which I have designated as "periodic" currents, can pass to actuate the ringer. From a point on the winding Q intermediate of its ends I take off a branch wire 10 to the transmitter T, from which a wire 11 passes to the hook-switch. A second intermediate branch wire 8 connects the No. 1 line-terminal with the point z, between the coil Q and the condenser C. The continuity of this wire 8 is normally interrupted at the switch, but is completed when the hook goes up. The talking-circuits are then as shown in the diagram, Fig. 3. In this figure I have omitted the switch-hook and springs for the sake of clearness and simplicity 85 and have shown the line-wires connected through points z z representing jack and plug contacts to the main battery S, supposed to be bridged across the cord at 3 3. Line-wire 1 extends from the central office to the 90 substation, where it is connected to the extremities of the coil Q by wires 8 and 9. Line-wire 2 similarly extends to the substation and is there connected to the transmitter T and receiver R by the wires 11 and 13, respectively. From the receiver the wire 12 extends to the outside terminal of the condenser C, and from the transmitter the wire 10 extends to the point z' on the coil Q intermediate of its ends. The two portions of the winding (marked q² and q³) may be made anything desired by shifting the point of connection z'. If they are equal—that is, if in a coil having a total resistance of one thousand ohms they are each of five hundred ohms resistance—being in parallel in the transmitter-circuit its resistance will be two hundred and fifty ohms plus the internal resistance in the transmitter—say fifty ohms—or a total of three hundred ohms. This can be made 105 smaller to any desired degree by selecting a point z' near one terminal of the coil. 110

Obviously for talking-currents over the line the path 8, C, 12, R, 13, is closed, while for battery-current the transmitter-path alone, 8, 9, q², q³, 10, T, 11, is closed. 120

I may also so arrange the contacts on the switch-hook that the condition in Fig. 3^a is produced in talking with the hook up, the receiver and condenser then being in a shunt around the coil and in the direct path of speech-currents through the transmitter. 125

It will be observed that by my arrangement I utilize the ringer-winding as such for ringing and as an impedance-coil when the tele- 130

phone is in use, saving thereby the separate impedance-coil commonly used. I also produce a self-contained telephone set without separate condenser or impedance-coil, as commonly employed, thereby not only effecting a marked economy, but reducing the size of the set and the number of parts and connections, making it much easier to transport, to install, and to maintain in order.

10 I am aware that many changes may be made in the apparatus I have illustrated and described without departing from the spirit of the invention, and I wish it understood that I contemplate all such changes as within the 15 scope and purview of my claims.

Having thus described my invention, what I claim, and desire to secure by Letters Patent, is—

1. A subscriber's telephone set comprising a frame, a pair of cores mounted on said frame, a magnet-winding on one core and a condenser-winding on the other, a plate supported on said frame, a hook-switch mounted on said plate, and terminals also thereon, together with an 20 armature for the cores and a gong-striker controlled thereby, a receiver and transmitter, and circuit connections therefor such that in one position of the hook-switch the magnet-winding and condenser are in series for ringing, and in another they are connected with the transmitter and receiver respectively, for talking, substantially as described.

2. A common-battery telephone set comprising a ringer-magnet, an armature therefor 25 carrying a clapper, and gongs coöperating therewith, a transmitter and a receiver, and

means to switch the ringer-winding into the transmitter-circuit to serve as an impedance-coil during use of the instrument, substantially as described.

40

3. A self-contained telephone set comprising a box or casing, a pair of gongs mounted on said casing, a yoke secured within the casing, a ringer-magnet and a condenser supported on said yoke, a side plate also supported on the yoke, switch-contacts secured on the plate, a hook-lever pivoted to the plate and controlling said contacts, and circuit connections, substantially as described.

45

4. In a telephone system, the subscriber's 50 circuit comprising line-terminals, a ringer-magnet adapted to be normally connected to said terminals for receiving signals over the line, a receiver, a transmitter, means to switch the windings of said ringer-magnet windings 55 into circuit with the line and the transmitter while the instrument is in use, and means to supply current to the transmitter through said windings, substantially as described.

5. In a common-battery telephone system, 60 substation-circuits comprising a signal-receiving branch and a transmitter branch, a ringer-magnet, and means to switch said magnet into the signal branch for receiving signals, and into the transmitter branch to serve as an impedance, substantially as described.

In testimony whereof I affix my signature in presence of two witnesses.

CHARLES E. EGAN.
